UNITED STATES PATENT OFFICE.

MARSHAL WHEELER, OF BOSTON, MASSACHUSETTS.

INCANDESCENT ELECTRIC LAMP.

SPECIFICATION forming part of Letters Patent No. 374,224, dated December 6, 1887

Application filed February 4, 1887. Serial No. 226,571. (No model.)

To all whom it may concern:

Be it known that I, MARSHAL WHEELER, of Boston, in the county of Suffolk and State of Massachusetts, have invented a certain new and useful Improvement in Incandescent Electric Lamps; and I do hereby declare the following to be a full, clear, and exact description of the invention, such as will enable others skilled in the art to which it pertains to make and use it, reference being had to the accompanying drawings, which form part of this specification.

My invention relates to an improvement in incandescent electric lamps; and it consists in the combination of a suitable holder, frame, or cup, which is filled with an amorphous mass of zirconia, with a number of pairs of carbons which extend into the frame or cup, and around the points of which the zirconia is packed, each pair of carbons being connected to opposite poles of a suitable battery, whereby the currents of electricity are made to flow in opposite directions, meeting and passing each other at a common center, as will be more fully described hereinafter.

The object of my invention is to obtain a greater degree of heat, and consequently a greater incandescence at a given point, than has hitherto been found possible in incandescent lamps.

Figure 1 is a perspective of a lamp embodying my invention. Figs. 2 and 3 are horizontal vertical sections taken through the body of the lamp and showing connections of the carbons to the batteries.

A represents the cup or frame, which may be given any desirable shape, and which is made of platinum, soapstone, or any other suitable material which will withstand the intense heat which is generated by the currents of electricity passing through it. Extending horizontally through suitable binding-posts, B, which are arranged in any desired relation to the cup A, and through the sides of the cup A, are the carbons C, which are arranged in pairs, as shown, the inner points of the carbons being made to approach each other at a common center. These carbons are insulated from the cup A, if so desired, and have their inner ends completely surrounded

by a mass of amorphous zirconia, which is 50 packed in the cup. To the outer end of each of the carbons C is connected one of the wires leading from one of the poles of a suitable battery. For each pair of carbons there is a 55 separate and distinct battery, D, and the carbons are connected to the wires of the battery, as shown in Figs. 2 and 3. The currents of electricity in passing through the carbons meet and pass each other at the points of the carbons.

The carbon may be made of one solid piece, or composed of a number of pieces, so as to form one whole. These carbons may be used with or without a vacuum, just as may be preferred.

The zirconia, being packed solidly around the points in the cup, acts as a protector from the atmosphere, and hence the carbons are burned away very slowly. The kind of spring used, or the point to which it is attached at 70 its fixed end, is immaterial.

In making all four carbons in one solid piece, as shown, they can be inserted more quickly into position than where they are made separate and distinct, and without any 75 necessity for adjusting their points in relation to each other. In order to allow the carbons to be placed in position in one solid mass, the edge of the cup must, of course, be provided with movable blocks or pieces, 80 which can be removed, and then the carbons slipped down into the position, as shown in Fig. 1.

Having thus described my invention, I claim—

1. In an electric lamp, the combination of a suitable frame or holder, containing an amorphous mass of zirconia, with the carbons arranged in pairs and connected to different batteries, substantially as shown.

2. In incandescent lamps, the combination of a suitable frame, containing a mass of amorphous zirconia, with carbons which have their inner ends passed through the frame, which have their inner ends surrounded by 95 the zirconia, and which are connected to different batteries at their outer ends, whereby the currents of electricity meet and pass each

other at a common center, substantially as set forth.

3. A series of different carbons which are molded in one solid piece and connected together at their inner ends, so that the currents of electricity will pass from one to the other, substantially as set forth.

In testimony whereof I affix my signature in presence of two witnesses.

MARSHAL WHEELER.
